UNITED STATES PATENT OFFICE

2,432,596

AMUSEMENT TARGET

John Goodill Tindale, Iola, Kans.

Application April 17, 1944, Serial No. 531,409

2 Claims. (Cl. 273—102.1)

1

My invention relates to amusement devices, and has among its objects and advantages the provision of an improved comic figure serving as a target for balls thrown thereat in the spirit of a competitive game or for throwing practice.

In the accompanying drawing:

Figure 1 is a face view of the target;

Figure 2 is a side view;

Figure 3 is a fragmentary rear view of the head structure;

Figure 4 is a sectional view taken substantially along the line 4—4 of Figure 3;

Figure 5 is a sectional view taken along the line 5—5 of Figure 3; and

Figure 6 is a side view of a modified form of construction.

In the embodiment selected for illustration, I make use of a base 10 to which is fixedly secured an upright post 12 braced by a diagonal member 14. To the post 12 is fixedly connected a bracket 16 having a depending and vertical end portion 18 secured to a target 20 in the nature of a comic figure. The end portion 18 is made secure by screws 22. The target 20 is cut from a wooden board or plank of sufficient thickness to withstand the punishment inflicted by balls thrown thereagainst.

The head portion 24 of the target includes a relatively large mouth opening 26 normally closed by two doors 28 and 30. According to Figure 1, the doors 28 and 30 have angular faces 32 fitting the correspondingly shaped wall faces of the mouth opening 26, with the doors normally closing the mouth opening in the plane of the figure. Metallic reinforcement 34 is attached to the figure 20 about the mouth opening.

Hinges 36 pivotally connect the door 28 with the head portion 24, while hinges 38 also pivotally connect the door 30 with the head portion. Figure 1 illustrates the doors 28 and 30 as being provided with markings simulating teeth 40.

To the rear face of the head portion 24 is fixedly secured a body 42 which supports a bell 44 arranged to be struck by a hammer 46 attached to the door 28. The door 28 swings upwardly when struck by a ball for bringing the hammer 46 into striking engagement with the bell. When a ball strikes the door 30, this door pivots downwardly to the dotted line position of Figure 4 to rest on a horizontal bar 48 serving as a closure for the door 30 through upward movement of the bar. This bar normally lies at rest on a support 52 attached to the figure 20. Two ropes 54 are attached to the bar 48 and extend loosely through openings 56 in the sup-

2

port 52. Weights 58 are attached to the lower ends of the ropes 54.

Two ropes 60 are attached to the bar 48 and pass through openings 62 in the body 42. To the body 42 and the support 52 are fixedly connected two vertical guide rods 64 extending loosely through openings in the bar 48 to guide the latter in its vertical movement. Both ropes 60 respectively pass around grooved wheels 66 and are tied to a pull rope 68. Thus a pull on the rope 68 elevates the bar 48 for pivoting the door 30 to a closed position, the door 28 gravitating to its closed position. The weights 58 return the bar 48 to its position at rest on the support 52 when the rope 68 is released. The hinges 38 are so located that the door 30 will rest firmly against the tapered wall face of the mouth opening.

The ropes 60 and the guide rods 64 are spaced sufficiently far apart to permit the doors 28 and 30 to swing freely therebetween.

Figure 6 illustrates a modification in that the figure 70 includes a mouth opening 72 devoid of doors. A bell 74 is attached to a rope 76 depending from the bracket 78. A plate 80 is attached to the rope 76 in line with the mouth opening 72 and slightly rearwardly of the target. Thus a ball thrown through the mouth opening will strike the plate 80 and cause the bell 74 to ring.

Without further elaboration, the foregoing will so fully illustrate my invention, that others may, by applying current knowledge, readily adapt the same for use under various conditions of service.

I claim:

1. A ball target comprising a figure having a mouth opening, a bell, upper and lower doors pivoted about horizontal axes on said figure and normally closing said mouth opening, with the upper door gravitating to its normally closed position, said doors being marked to simulate teeth, a bell striker attached to one of said doors for engaging the bell through pivotal movement of that door when struck by a ball thrown in said mouth opening, weighted means normally lying underneath the lower door to support the latter when pivoted to an open position, and pull means connected with said weighted means for elevating the latter and closing the lower door.

2. A ball target comprising a figure having a mouth opening, a bell, upper and lower doors pivoted about horizontal axes on said figure and normally closing said mouth opening, with the upper door gravitating to its normally closed position, said doors being marked to simulate teeth, a bell striker attached to one of said doors for engaging the bell through pivotal move-

ment of that door when struck by a ball thrown in said mouth opening, weighted means normally lying underneath the lower door to support the latter when pivoted to an open position, pull means connected with said weighted means for elevating the latter and closing the lower door, and means fixed to said figure for guiding said weighted means, the latter including a horizontal door-engaging bar having weights connected therewith, and a line means for elevating the bar to close the door.

JOHN GOODILL TINDALE.
